SUGAR BOWL WITH LID

Viktor Schreckengost, Cleveland, Ohio, assignor to The Salem China Company, Salem, Ohio, a corporation of Ohio

Application April 7, 1955, Serial No. 35,400

Term of patent 14 years

(Cl. D44—15)

I claim:

The ornamental design for a sugar bowl with lid, as shown.
